UNITED STATES PATENT OFFICE.

JOSEPH DAVIS WESTGATE, OF SAN FRANCISCO, CALIFORNIA.

IMPROVED SAD-IRON HOLDER.

Specification forming part of Letters Patent No. 75,611, dated March 17, 1868.

To all whom it may concern:

Be it known that I, JOSEPH DAVIS WESTGATE, of San Francisco, county of San Francisco, State of California, have invented an Improved Sad-Iron Holder and Shield; and I do hereby declare the following description and accompanying drawings are sufficient to enable any person skilled in the art or science to which it most nearly appertains to make and use my said invention or improvements without further invention or experiment.

My invention consists in providing a sad-iron holder with a lining of non-conducting substances, so that the hand grasping the holder will not be burned by the handle of the sad-iron. To prevent the radiation of the heat from the body of the iron to the back of the hand and fingers, a shield is attached beneath the holder by wires, which are bent so as to partially inclose the handle, while the shield is below the grasping-hand. This shield is also lined with a non-conducting substance.

In order to more fully illustrate and describe my invention, reference is had to the accompanying drawings and letters marked thereon, of which—

Figure 1 is a sectional elevation. Fig. 2 is a plan of the shield.

A represents the pad or principal part of the holder, the bottom portion of which may be of leather or any other suitable material, and copper wire *a a* may be placed transversely across it to prevent the handle from coming into immediate contact with the leather. I line the pad with suitable thicknesses of cloth, (flannel will answer very well,) and between it and the lining I spread a coating of plaster-of-paris *b*, or other non-conducting substance. Over the top of the whole a flannel lining *C* is placed which extends beyond the circumference of the pad at one side and is turned up to afford a pocket

for the fingers. At the other side is attached a piece of cloth *C'* for a thumb-holder. The edges of the pad and holders are bound with any suitable material, which serves to keep the whole together.

Below the holder is a shield *B*, of suitable size to enter between the posts of the sad-iron handle, and is attached to the holder at each side by copper wires *d d*, curved so as to partially fit around the handle at *d'*. The shield is curved and the upper surface lined with cloth *e*, and a non-conducting substance of plaster-of-paris or other suitable material placed on the shield beneath the cloth lining, where it is held by turning up the edge of the shield, which is easily performed when thin metal is used for constructing the shield. By this means a simple holder and shield is had, completely protecting the hand from the direct heat of the handle of the sad-iron as well as from the radiation of the heat from the sad-iron itself, which is oftentimes very painful.

Having thus described my invention, I am well aware that a round pad or holder with strips of metal attached to the face is known and in use. I therefore do not claim, broadly, a pad or holder with metal bars across its face.

What I do claim, and desire to secure by Letters Patent, is—

A sad-iron holder constructed with pockets for the thumb and fingers and with an interlining of gypsum or other similar non-conducting substance, in combination with a shield *B*, having a similar interlining or covering, substantially as described.

In witness whereof I have hereunto set my hand and seal.

JOSEPH DAVIS WESTGATE. [L. S.]
